CLAIM

The ornamental design for a tea kettle, as shown and described.

DESCRIPTION

FIG. 1 is a side elevational view of a tea kettle showing our new design, the opposite side being a mirror image;

FIG. 2 is a top plan view thereof;

FIG. 3 is a front elevational view thereof;

FIG. 4 is a bottom plan view thereof; and

FIG. 5 is a rear elevational view thereof.

*FIG.1**FIG. 3*

FIG.5
